UNITED STATES PATENT OFFICE.

WILLIAM SCHMITZ, OF NEW YORK, N. Y.

COMBINATION LOCK.

Application filed February 7, 1922. Serial No. 534,675.

To all whom it may concern:

Be it known that I, WILLIAM SCHMITZ, a citizen of the United States, residing at New York, in the county of New York and State of New York, have invented certain new and useful Improvements in Combination Locks, of which the following is a specification.

This invention relates to improvements in permutation locks adapted to be used on doors, windows and like closures.

The device consists principally of a casing containing elements of simple construction arranged to operate locking bolts engaged in the casing and initially advanced and retracted by means of a handle passing thru the door.

Provision of means is provided for preventing the bolts from retraction until a series of slotted discs have been positioned to register the bolt end, and rotation of the discs is accomplished by manipulation of a graduate dial mounted on a sleeve, passing thru the door and causing the discs to be rotated.

Other objects of importance are attained by the novel construction and arrangement of parts hereinafter described and shown in the accompanying drawings, forming a material part of this disclosure and in which:

Figure 1 is a front elevational view of a door and transom showing the device arranged thereon.

Figure 2 is a plan view of the graduated dial and mounting plate. Figure 3 is a fragment of a door with the lock attached and having the cover broken away to show the interior members.

Figure 4 is a right hand elevational view of the same.

Figure 5 is a horizontal sectional view of the permutation elements as they appear on the line 5—5 of Figure 3.

Referring to the drawings, the numeral 10 designates a door of conventional type secured by hinges 11 to a door casing 12, over which is a transom 13 hinged as at 14 and a bolt 15, vertically slidable in brackets 16 and 17, is adapted to engage within a bracket 18 secured to the top of the door casing 19, thus locking the transom when the bolt is raised by means hereinafter described. A pin 15' is fixed in the bolt and being contactable with the upper side of the bracket 16, prevents it from dropping far enough to contact with the bracket 24, the transom being free to be opened or closed as desired.

Attached on the inside of the door 10 is the lock 20, provided with suitable bolt elements 21 and 22, the upper end of the bolt 21 being guided by a bracket 23 fixed to the top of the door and adapted, when extended, to enter a similar bracket 24 attached to a cross member 25 disposed longitudinally between the door casing 12 and separating the door and transom members.

The lower bolt 22 passes thru another bracket 26 and is thereby guided into a recess 27 formed in the floor 28, when lowered.

Referring to Figures 3 and 4, the lock in general is indicated by the numeral 20 and comprises a base plate 29 having a pair of integral raised blocks 30 and 31 thru which are longitudinally aligned openings receptive of the slidable cylindrical locking bolts 21 and 22.

A cover plate 32 is supported from the base plate 29 by spacing collars 33 and held in position by suitable screws 34.

An actuating bar 35, angularly bent at one end, is secured to the upper bolt 21 by a pin 36 engaged thru the bar and bolt, and the opposite end of the bar is pivotally connected by a shoulder screw 37 to a lug formed at one end of a lever 38, having a raised central portion in which is a transverse opening 39 thru which the lock bolt is free to operate.

Integral with the top of the lever 38, is a pintle 40 rotatable in an opening in the cover plate 32, and its projecting end 41 is squared, receptive of a key for manipulating the lever from the inside of the door.

The lever 38 is pivotally connected to the base plate 29 by a screw 42 passing thru the bottom of the lever, in line with the pintle 40 and engaged in the end of a lock lever operating spindle 43 mounted to pass thru the door 10 and the base plate 29, and secured to the spindle 43, is a bevelled disc 44. The outer end 45 of the spindle 43 is squared to receive a key 46 for oscillating the lever 38, this key or wrench being removable and interchangeable on the squared end of the pintle 41.

An angle plate 47 has secured in its outwardly extending element 48, a pin 49 operably extending thru a guide way 50 and into an opening 51 cross drilled into the locking bolt 22. A link 52 is pivoted at one end to the bottom of the angle plate 47, the other end of the link being pivoted to the lug 53 of the lever 38; screws 54 being employed for pivotal engagement.

Referring to Figures 3 and 4, it will be seen that as the spindle 43 is rotated to the right or left an oscillating motion is imparted to the lever 38, and the lever end 53, thru the link 52 and the pin 49, causes the locking bolt 22 to move vertically and parallel thru the bearing block 31 and the opening in the lever 38.

It will also be seen that as the opposite 10 end of the lever 38 is oscillated, the locking bolt 21, by its connection with the bar 35, is moved reciprocatively but opposite from the locking bolt 22.

The permutation locking elements, best 15 shown in Figure 5, comprise a spindle 60 rotatable in a sleeve 61 passing thru the door 10 and extending into the lock casing.

At the outer end of the spindle 60 is a bevelled disc 62 having graduations thereon 20 numbered from 0 to 100.

A knurled handle 63 is provided for rotating the spindle 60 and is secured to it by a pin 64. A ring 65 is centered by the sleeve 61 and secured to the front of the 25 door 10, this ring having a shallow recess 66 receptive of the dial 62 and a line 67 coinciding with the 0 line of the disc is formed on the face of the ring.

Letters L and R are also impressed on the 30 ring for indicating the left or right hand direction in which the dial 62 should be turned to release the locking elements.

A plurality of discs 68, 69, 70 and 71 are rotatably mounted on the inner end of 35 the sleeve 61, the discs 69, 70 and 71 having curved tumbler races or openings respectively 74, 73 and 72, their inner radii being uniform and their outer radii progressively increasing, producing races of unequal 40 width.

Rigidly fixed in the innermost disc 68 are a pair of widely spaced tumbler pins 75, the same extending through the several races to points beyond the outermost disc 71.

In a similar manner pairs of pins 76, 77 and 78 are set respectively in the intermediate discs 69 and 70 and outer disc 71, all of the several pins extending outwardly so that their ends are in the same plane.

An arm 79, secured by its hub to the inner portion of the spindle 60, is adapted to contact with these extending pins, upon twirling the knob 63, thereby rotating the discs in either direction necessary to bring the 55 notches 84, formed in all the discs into register as will be further on described, the end of the spindle 60 being housed in the cover plate 32.

The discs 68, 69, 70 and 71 while free to 60 oscillate on the sleeve 61, are confined and under slight frictional restraint between the flanged end 80 of the sleeve 61 and the collars 81 and 82, the former being closely adjacent the base plate 29 and tightly fitted 65 on the sleeve 61.

In Figure 3, the upper end of the lower locking bolt 22 is shown as a parallel sided tongue 83 adapted to enter into notches 84, formed radially thru each of the discs 68, 69, 70 and 71 at a point between the ends of 70 the tumbler races 72, 73 and 74.

From the foregoing it will be seen that a simple, practical and efficient combination lock has been described and which is operated in the following manner. 75

Figure 3 discloses the lock in a position in which the bolts may be repeatedly extended and retracted, the locking tongue entering the locking notches of the discs at each retraction of the bolts as they are 80 caused to operate by turning the key or handle 46 associated with the bolt operating mechanism of the lock.

When it is desired to lock the closed door, the bolts are shot outward and the dial handle turned in either direction, which movement causes the tumbler carrier 79 to contact with the tumbler pins and compelling the discs to be partially rotated. 85

It will be seen that rotary movement of 90 the discs will cause an overlapping of the notch elements 84, thus preventing the bolt tongue 83 from entering the notches of the discs.

It is further seen that each disc is provided with two tumbler pins, the carrier 79 operating therebetween, and when it is desired to unlock the door the dial is turned in such direction as will cause the carrier to strike the tumbler pins and the discs will 100 be rotated into position allowing the notches to receive the bolt tongue.

It will be understood that varying combinations may be arranged by varying the positions of the tumbler pins in the discs. 105

Although the foregoing is descriptive of the preferred embodiment of the invention, it will be apparent that minor changes may be made in its construction, without the exercise of invention or conflicting with the scope 110 of the claims hereto appended.

Having thus described my invention, what I claim as new and desire to secure by Letters Patent, is:—

1. A lock comprising a frame, a pair of 115 locking bolts slidable in opposite directions in said frame, a yoked lever pivoted in the frame, one of said bolts passing thru said yoke, a bar connecting one of said lever arms with the other bolt, an angle plate, a pin 120 fixed therein to engage with the last mentioned bolt, a link pivotally connecting said angle plate with one end of said yoked lever, and a spindle engaging said lever extending operatively outward, said spindle having a square outer end receptive of operating means for actuating the locking bolts.

2. A lock comprising manually operated locking bolts slidable in opposite directions, 130

a frame, a sleeve extending into said frame, a plurality of notched discs mounted on said sleeve, a spindle rotatable in the sleeve, a graduated dial attached to the outer end of 5 the spindle, tumbler pins in said discs, means for turning said discs in opposite directions until the notches therein are alined, a flattened extension on the inner end of one of said bolts adapted to enter the notches of 10 said discs when alined, a yoke operatively engaging both of said bolts, and means on said yoke for actuating said bolts simultaneously.

3. A combination lock comprising a cas- 15 ing, a pair of opposed cylindrical locking bolts and a permutation lock associated therewith, said lock comprising a tubular

sleeve, notched discs rotatable thereon, pairs of tumbler pins fixed in the discs, tumbler races formed in the discs through which 20 said pins extend, a spindle rotatable in said sleeve, means fixed to said spindle adapted to engage with said tumbler pins and cause said discs to be rotated to definite positions, a dial fixed on said spindle, said dial having 25 graduations representing angular arcs of travel required by the disc to attain alinement of the locking notches in said discs, a flattened end on one of said locking bolts to simultaneously enter all of the locking 30 notches when alined and means for actuating said bolts independently of said spindle.

In witness whereof I affix my signature.

WILLIAM SCHMITZ.
